CLIFFORD UTTER, OF LEBANON, INDIANA.

RAZOR-BLADE HOLDER.

No. 880,765.

Specification of Letters Patent. Patented March 3, 1908.

Application filed April 1, 1907. Serial No. 365,765.

To all whom it may concern:

Be it known that I, CLIFFORD UTTER, a citizen of the United States, residing at Lebanon, in the county of Boone and State 5 of Indiana, have invented certain new and useful Improvements in Razors, of which the following is a specification, reference being had therein to the accompanying drawing.

This invention relates to a safety razor 10 blade holder in which the blade may be readily secured in a manner to permit the convenient honing or stropping of the same.

Safety razors of the usual type include a cutting blade, which, for honing and stropping purposes, must be removed from its holder. As this blade is ordinarily of a thin 15 flexible character, it is obvious that an auxiliary holder must be provided for the reception of the blade when desiring to strop or 20 hone the same.

The main object of the present invention is, therefore, the provision of an auxiliary holder in which the cutting blade of a safety razor may be quickly and conveniently secured 25 in a manner to present the cutting edge of said blade for honing or stropping purposes.

Another object of this invention is the provision of an auxiliary holder particularly 30 adapted for the reception of the usual double-edge razor blades, wherein the edge not presented for honing or stropping is free of contact with any part of the holder and thereby protected against injury.

With the above object in view the invention 35 consists in separable clamping plates specifically formed for coöperation with the particular form of blade to be operated upon, a handle member secured to or formed integral 40 with one of the plates, and a binding clip to secure the plates in clamping engagement with the blade.

The preferred embodiment of details of the present invention will be described in the following 45 specification and particularly pointed out in the claims.

In the accompanying drawings like numerals of reference designate like parts throughout the several views.

Figure 1 is a perspective view of a holder 50 constructed in accordance with my invention; Fig. 2 is a sectional view of the same taken along the line 2-2 in Fig. 1; Fig. 3 is a perspective view of one of the clamping plates with the attached handle; Fig. 4 is a perspective view of the coöoperating clamping

plate; Fig. 5 is a perspective view of the binding clip; Fig. 6 is a perspective view of one form of safety razor blade with which the clamping plates shown in Figs. 3 and 4 are 60 particularly designed to coöperate; Fig. 7 is a perspective view of a modified form of clamping plate adapted to coöperate with the clamping plate shown in Fig. 3; Fig. 8 is a perspective view of another form of razor 65 blade for which the clamping plates shown in Figs. 3 and 7 are particularly designed; Fig. 9 is a perspective view of another form of clamping plate designed to coöperate with the clamping plate shown in Fig. 3 and arranged to secure razor blades of plain configuration; Fig. 10 is a perspective view showing a portion of the handle and attached 70 clamping plate differing from the plate shown in Fig. 3; Fig. 11 is a perspective view 75 of a clamping plate arranged for coöperation with the clamping plate shown in Fig. 10; and, Fig. 12 is a perspective view of a razor blade of plain configuration for which the clamping plates shown in Figs. 10 and 11 are 80 particularly adapted.

Referring to the drawings, and more particularly to Figs. 1 to 6 inclusive my improvement is seen to comprise a clamping plate 1, hereinafter termed the fixed clamping plate, 85 a second clamping plate 2, arranged to coöperate with the plate 1 and hereinafter termed a movable clamping plate, a handle member 3 integral with or otherwise secured to the fixed clamping plate 1, and a binding clip 4, 90 of a resilient material, adapted to embrace the clamping plates and secure them in clamping position.

The fixed clamping plate 1 is of comparatively thin material, though having sufficient 95 rigidity for the purpose designed, and is of somewhat greater length and width than the razor blade to be held thereby. The fixed clamping plate 1 is formed integral with, or otherwise permanently secured to the handle 100 3, preferably projecting with its outer surface in alinement with one side of the handle, as shown in Figs. 1, 3, and 10. As the handle 3 is of materially greater thickness than the thickness of the fixed clamping plate 1, the 105 described connection of the parts insured a projection of the handle beyond the relatively inner surface of the fixed clamping plate 1 to provide a shoulder 5.

The relatively outer surface of the fixed 110 clamping plate 1 inclines downwardly and inwardly throughout its width, the alined edge

of the handle member 3 forming a continuation of this incline. The relatively inner surface of the fixed clamping plate 1, however, presents two distinct surfaces, 6 and 7, each 5 occupying the full length and approximately one-half the width of the plate. The upper surface 6 inclining in exact parallel relation to the outer surface of the plate, while the lower surface 7 is arranged in a plane at direct 10 right angles to the lower edge or shoulder 5 of the handle member 3. As thus constructed, the fixed clamping plate 1 has a regularly inclined outer surface, and an inner surface made up in two distinct planes, the upper 15 plane being arranged parallel to the outer surface of the plate while the lower or clamping plane is disposed at an angle to the upper plane and at right angles to the longitudinal plane or surface of the edge of the handle 20 member 3.

The fixed clamping plate 1 is shown as adapted for the reception of a razor blade of a particular type, being for this purpose formed in that portion included in the surface 7, is provided with a series of, preferably 25 three, openings 8, and in the end edges, situated in alinement with the openings 8, with V-shaped notches 9.

The movable clamping plate 2 is identical 30 in size and structural formation with the fixed clamping plate 1, having the relatively outer surface inclined similar to the outer surface of the fixed clamping plate 1 and the relatively inner surface embracing two distinct planes 10 and 11, similar to the surfaces 35 6 and 7 of the fixed clamping plate 1. The movable clamping plate 2 is further provided with a series of projecting studs 12 designed, when the said plates are assembled in clamping 40 position, to engage the openings 8 in the fixed clamping plate 1.

The fixed clamping plate 1 and the movable clamping plate 2 as described, are designed for clamping and holding engagement 45 with a razor blade 13, shown in Fig. 6, which blade is of distinctive type in that it is formed with a series of longitudinally aligned openings 14 for coöperation with a particular part of a razor structure.

In Fig. 7 is illustrated another form of 50 movable clamping plate 15, designed to co-operate with the fixed clamping plate 1, and in all respects identical with the movable clamping plate 2, except that the studs 12 55 are omitted and the clamping surface of said movable clamping plate 15 is formed with V-shaped projections 16 to engage the V-shaped recesses 9 formed in the edges of the fixed clamping plate 1. This form of 60 movable clamping plate is particularly adapted for use in connection with another distinctive type of razor blade 17, shown in Fig. 8, which blade is formed with edge notches 18 for engagement with holding members 65 on the razor holder and whereby said

razor blade is also held in the auxiliary holder and prevented from moving either longitudinally or laterally when situated in position between the clamping plates.

In Fig. 9 is illustrated another form of 70 movable clamping plate, as 19, also identical with the plate 2, except that the studs 12 are omitted and the side edges of the plate are formed with laterally projecting flanges 20, designed to embrace and bear against the 75 end edges of the fixed clamping plate 1. The flanges 20 gradually decrease in width from one end to the other to insure coöperation between said flanges and the fixed clamping plate 1 in the clamping positions 80 of these plates and at the same time avoid projection beyond the outer surface of the fixed clamping plate 1. The movable clamping plate 19 is designed for use with any form of razor blade, being particularly 85 adapted, however, for those blades of plane surfaces and without particular means for coöperation with holding elements in the razor structure, as the plain razor blade 17, shown in Fig. 12 as well as those blades 90 shown in Figs. 6 and 8.

In Figs. 10 and 11 are illustrated coöperating clamping plates, a fixed clamping plate 21 and a movable clamping plate 22, similar in all respects to the clamping plates 95 1 and 2, except that through the connecting means provided on these plates they are adapted for clamping any form of razor blade. The connecting means comprise edge projecting flanges 23 formed on the relatively lower half of the fixed clamping plate 21, and interlocking and co-acting edge flanges 24 formed on the relatively upper half of the removable clamping plate 22. With the plates 21 and 22 assembled in 100 clamping relation, the respective flanges 23 and 24 interlock and co-act to maintain said clamping plates against independent longitudinal and lateral movement.

A binding clip 4, of a resilient material, as 110 steel plate, is used to retain all the above described forms of coöperating clamping plates in clamping positions, said clip comprising a spring strip bent to embrace the handle member and to provide spring leaves 25 to bear against the relatively outer surfaces of the clamping plates and exert sufficient pressure thereon to hold the razor blade in fixed relation therebetween.

Assuming the auxiliary holder constructed 120 as shown in Figs. 1 to 6 inclusive, and the blade to be operated upon, such as shown in Fig. 6, said blade is engaged with the movable clamping plate 2 by passing the openings 14 over the studs 12. The movable 125 clamping plate 2 and the blade 13 applied thereto is then arranged in position on the fixed clamping plate 1, by passing the studs 12 through the openings 8. The clip 4 is then passed over the handle member and 130

connected clamping plates by a relatively endwise movement of the parts until the free edges of the leaves 25 bear against the outer surfaces of the said clamping plates. 5 The razor blade is thus clamped in position with one of the cutting edges thereof projecting beyond the free edges of the clamping plates, in which position said edge may be honed or stropped in the usual manner.

10 In securing the blade shown in Fig. 8 in the auxiliary holder, the movable clamping plate 15 is of the form shown in Fig. 7, in the use of which the projections 16 engage the notches 18 in the razor blade and also the notches 9 in the fixed clamping plate 1. The 15 binding clip 4 thereupon applied as previously described, to complete the clamping of the razor blade.

In the use of the auxiliary holder with 20 blades of other types the clamping plate 19 may be used with the fixed clamping plate 1, but I prefer to use clamping plates such as the clamping plates illustrated in Figs. 10 and 11, which plates 21 and 22 are especially 25 adapted to coöperate to clamp any form of blade of this character of razor between their clamping surfaces, the clip 4 being applied to said plates to complete the clamping operation.

30 The relative inclinations of the upper and lower portions of the inner proximate surfaces of the respective clamping plates is a very material feature of the present invention. Owing to these inclinations, the lower 35 portion of the inner of each clamping plate will snugly engage the interposed razor blade, while the upper portions of these surfaces diverge from their connection with the engaging surfaces to the handle member, so that when the clamping plates are in clamping 40 position the upper portions of the inner surfaces are spaced apart, as shown in Fig. 2. As practically all blades for safety razors are of the double type, that is, with opposing 45 cutting edges, the construction described will clamp the blades to permit operation upon one cutting edge while at the same time supporting the other cutting edge in the space provided between the upper portions 50 of the inner surfaces of the plates. The cutting edge is so supported as to be absolutely free from contact with any portion of the holder, and is thereby prevented from injury during the honing or stropping 55 of the other cutting edge.

It is to be particularly noted in connection with the auxiliary holder described, that the fastening means is such that the blade may be secured in the auxiliary holder or removed 60 therefrom in a simple and convenient manner. Furthermore, the particular arrangement of the clamping plates permits the use of a handle member of sufficient strength and rigidity to insure a proper honing and 65 stropping of the razor blades, as any inher-

ent flexibility in the handle member would materially interfere with a proper treatment of the razor blade.

While preferring the details of the structure shown and described, it is evident that 70 various changes and modifications may be resorted to without affecting the function of the device, and it is, therefore, to be understood that I do not limit myself to the precise arrangement described, considering as with- 75 in the spirit of the present invention such changes and variations as may fall within the scope of the appended claims.

I claim:—

1. A razor blade auxiliary holder comprising coöperating clamping plates, the proximate surfaces of the plates being relatively divergent for a portion of their widths, the remaining portions of said surfaces being projected in parallel planes to provide clamp- 80 ing faces.

2. A razor blade auxiliary holder comprising a handle member, a fixed clamping plate carried thereby, a movable clamping plate arranged to coöperate with the fixed clamping 90 plate, the proximate surfaces of the plates being relatively divergent for a portion of their widths the remaining portions of said surfaces being projected in parallel planes to provide clamping surfaces, and means en- 95 gaging both plates to secure them in clamping position.

3. A razor blade auxiliary holder comprising a handle, member, a fixed clamping plate carried thereby, a movable clamping 100 plate arranged to coöperate with the fixed clamping plate the proximate surfaces of the plates being relatively divergent for a portion of their widths, the remaining portions of said surfaces being projected in parallel 105 planes to provide clamping surfaces, means for retaining the razor blade in proper position between the clamping plates, and means for engaging both the clamping plates to secure them in clamping position. 110

4. A razor blade auxiliary holder comprising a handle member, a fixed clamping plate carried thereby, a movable clamping plate arranged to coöperate with the fixed clamping plate, the proximate surfaces of the 115 plates being relatively divergent for a portion of their widths, the remaining portions of said surfaces being projected in parallel planes to provide clamping surfaces, a binding clip embracing the handle member and 120 engaging both the plates.

5. A razor blade auxiliary holder comprising a handle member, a fixed handle plate carried thereby, a movable clamping plate arranged to coöperate with the fixed clamp- 125 ing plate, the proximate surfaces of the plates being relatively divergent for a portion of their widths, the remaining portions of said surfaces being projected in parallel planes to form clamping surfaces, means for retaining 130

said clamping plates in their relative positions, and a binding clip embracing the handle member and engaging both plates.

6. A razor blade auxiliary holder comprising a handle member, a fixed clamping plate carried thereby, a movable clamping plate arranged to coöperate with the fixed clamping plate, the proximate surfaces of the respective clamping plates being formed with 10 parallel clamping portions and divergent portions to provide a space between said plates when in clamping position, and means for securing the plates in clamping position.

7. A razor blade auxiliary holder comprising a handle member, a fixed clamping plate extending therefrom, a movable clamping plate arranged to coöperate with the fixed clamping plate, the relatively outer surfaces of the respective plates being inclined toward each other from the handle member, and a binding clip embracing the handle member and bearing upon the inclined surfaces of the plates.

8. A razor blade auxiliary holder comprising a handle member, a fixed clamping plate carried thereby, a movable clamping plate arranged to coöperate with the fixed clamping plate, the proximate surfaces of the respective clamping plates being formed with 25 parallel clamping portions and diverging portions to provide a space between said plates when in clamping position, laterally

projecting flanges formed on the side edges of said removable clamping plate and means for securing said plates in clamping position. 35

9. A razor blade auxiliary holder comprising a handle member, a fixed clamping plate carried thereby, a movable clamping plate arranged to coöperate with the fixed clamping plate, the proximate surfaces of the respective clamping plates being formed with 40 parallel clamping portions and diverging portions to provide a space between said plates when in clamping position, laterally interlocking projecting flanges formed on 45 the side edges of said clamping plates and means for securing said plates in clamping position.

10. A razor blade auxiliary holder comprising a handle member, a fixed clamping plate extending therefrom, a movable clamping plate arranged to coöperate with the fixed clamping plate, the relative outer surfaces of the respective plates being inclined toward each other from the handle member, 50 and a spring binding clip spanning the handle member and bearing upon the outer inclined surfaces of the clamping plates.

In testimony whereof I affix my signature in presence of two witnesses.

CLIFFORD UTTER.
